SLACK ADJUSTER

John A. Buvelot, Chicago, Ill., assignor to American Steel Foundries, Chicago, Ill., a corporation of New Jersey

Application February 27, 1956, Serial No. 567,900

3 Claims. (Cl. 287—58)

This invention relates to slack adjusters and more particularly to a slack adjuster arrangement adapted for use with railway car brakes.

The invention comprehends a slack adjusting device comprising a frame formed on the end of a tie rod or other element of the brake linkage, a unitary brake lever fulcrum block assembly slidably disposed within the frame, and a manually operated screw mechanism interconnecting the block and frame and operable to vary the position of the block in the frame in order to take up slack in the brake linkage.

Although slack adjusters of this general type have been heretofore employed in brake riggings, most of the conventional arrangements employ a brake lever fulcrum block assembly including a plurality of parts pinned or bolted together. Because of the tremendous stresses to which these fulcrum block assemblies are subjected, the advantages of a unitary assembly are obvious. However, the problem of assembling such a device has prohibited, until now, the design of a slack adjuster with a unitary fulcrum block assembly.

It is therefore a primary object of this invention to provide an improved slack adjuster having a unitary fulcrum block assembly.

Another object of the invention is the provision of a slack adjuster having a unitary fulcrum block assembly in interlocking sliding engagement with the frame.

A further object of the invention is the provision of a slack adjuster comprising a frame having a fulcrum block movably retained therein by a pair of auxiliary plates.

A more specific object of the invention is the provision of a slack adjuster comprising a frame having a movable fulcrum block retained therein by means of a pair of retaining plates rigidly secured to the block to provide a unitary fulcrum block assembly slidably engageable with the frame.

These and other objects of the invention will be apparent from an examination of the following description and drawings, wherein:

Figure 1 is a fragmentary top plan view of a slack adjusting device embodying features of my invention,

Figure 2 is a fragmentary side elevational view of the structure illustrated in Figure 1, and

Figure 3 is an end elevational view of the structure illustrated in Figure 1, with portions of the frame shown in vertical section.

Referring now to the drawing for a better understanding of the invention, it will be seen that a tie rod indicated generally at 10 is disclosed as having formed at one end thereof a frame 12 comprising spaced longitudinally extending arms 14 and 16 joined at their opposite ends by a wall 18 to present a closed slot 20 therebetween.

Disposed within the slot 20 for sliding movement longitudinally of the frame is a fulcrum block assembly indicated generally at 22 adapted to fulcrum a brake or truck lever 24. The right hand extremity (not shown) of the tie rod is normally connected to another lever or link (not shown) of the brake rigging.

2

The fulcrum block assembly, as best seen in Figure 3, includes a pair of substantially L-shaped retaining plates 26, each of which comprises a substantially flat side element 28 and a substantially flat end element 30 preferably formed integrally with the side element and extending outwardly therefrom and normally thereto.

The plates 26 are positioned at opposite sides of slot 20 with the outer surfaces 29 and 31 of the side and end elements 28 and 30, respectively, disposed in sliding engagement with the inner and upper surfaces 33 and 35, respectively, of the arms 14 and 16.

The fulcrum block 38 comprises a pair of substantially flat spaced side walls 40 interconnected at one end by a hub 42 and having webs or flanges 44 preferably formed integrally therewith and extending outwardly from the lower edges thereof.

The side walls 40 of the fulcrum block and the side elements 28 of the retaining plates are provided with longitudinally and vertically extending slots 45 and 47, respectively, which overlap adjacent their closed ends and which serve to retain in position a fulcrum pin 48 about which the lever 24 is pivoting or fulcrumed.

The fulcrum block 38 is positioned between the retaining plates 26 and is rigidly secured thereto preferably at the upper end thereof as by welds 25, with the side walls 40 of fulcrum block 38 being disposed parallel to and abutably engaging the insides of retaining plate side elements 28, and with the side wall flanges 44 extending outboardly to provide interlocking engagement between the fulcrum block assembly and the frame.

To vary the position of the fulcrum block assembly within slot 20 of the frame, a manually operated screw indicated generally at 50 is employed to connect the assembly to the frame.

The screw 50 comprises a head 52 having an integrally elongated threaded body 54 disposed to extend through frame wall aperture slot 49 and into frame slot 20 where the end 55 of the body is received in fulcrum block assembly hub recess 57. The screw body end 55 may be detachably secured to the fulcrum block assembly hub in any desired manner as by cotter 59.

To assemble the device, the retaining plates 26 are positioned in opposite sides of the slot 20 in engagement with respective arms 14 and 16 of the frame as above described.

A brake lever 24 is fulcrumed to the fulcrum block by inserting pin 48 into the open end of fulcrum block slots 45. The fulcrum block is then inserted between the retaining plates 26 from the bottom as seen in Figure 3 with the ends of the pin 48 being received in the open ends of the retaining slots 47. Once positioned, the fulcrum block is rigidly secured to the plates by welds 25 to form a unitary fulcrum block assembly. The body 54 of the screw 50 is then threaded through frame wall aperture 49 and inserted in fulcrum block hub aperture 57 and nonrotatably secured to the fulcrum block hub by the cotter 59. In order to prevent the accidental withdrawal of the screw from the frame, a key 61 may be inserted through the screw at a point adjacent the fulcrum block hub.

In describing the operation of the assembly, it will be understood that adjustment of a brake shoe must occur by moving the brake shoe fulcrum point towards the wheel. In the disclosed invention, this movement occurs when the pin 48 moves away from wall 18, or to the right as seen in Figures 1 and 2. For purposes of illustration, it will be assumed that screw 50 is retracted from the slot 20 but is in its assembled position with respect to the fulcrum block. When it is desired to adjust the brake shoe, cotter 59 is withdrawn from the assembly. Screw 50 is then rotated so as to be protracted or moved into the slot 20 and to thereby move the ful-

crum block to the right or away from wall 18. As soon as the desired adjustment is attained, rotation of screw 50 is stopped and cotter 59 is then reinserted in the fulcrum block hub and the screw end and the assembly is thus maintained at the desired position.

The key 61 merely serves to prevent the screw body from being withdrawn completely from the frame at the time of retraction of the screw.

I claim:

1. In a brake slack adjuster, a combination of: a frame comprising spaced arms interconnected at their ends and presenting a longitudinally extending slot therebetween, said arms having opposed lateral edges, a unitary fulcrum block assembly disposed within said slot and movable longitudinally thereof, said assembly comprising a fulcrum block having a pair of spaced side walls interconnected at one end thereof by a hub, said side walls being spaced from the arms, said side walls having flanges extending outwardly thereof and being engageable with corresponding lateral edges of the frame arms, a pair of L-shaped retaining plates interposed between the side walls and the frame arms, said plates slidably engaging said frame arms, said plates precluding sliding engagement between said side walls and frame arms, said plates having side elements extending outwardly therefrom and engaging opposite lateral edges of the frame arms, said plates being rigidly secured to said fulcrum block, a pivotal connection at the end of said assembly remote from said hub for connecting an associated brake element to said assembly, and means interconnecting the hub and the adjacent end of the adjuster whereby predetermined movement of the assembly may be affected.

2. In a brake slack adjuster, the combination of: a frame comprising a pair of spaced arms interconnected at their ends, said arms defining a longitudinally extending slot, a unitary fulcrum block assembly disposed within said slot, said assembly comprising a pair of plates disposed within said slot, each of said plates having a pair of elements, one of said plate elements being disposed within said slot in complementary sliding engagement with a related frame arm, the other of said plate elements being disposed outside of said slot in interlocking engagement with said related frame arm, a fulcrum block dis-

posed within said slot between said plates and fixed thereto, said block comprising a pair of walls interconnected at their ends by a hub, said walls being spaced from said frame arms, said walls comprising flanges disposed outside of said slot, said flanges extending outwardly from said block in interlocking engagement with said frame arms, means interconnecting the block hub and the related end of the frame for selectively positioning said assembly, and a pivotal connection formed by said block arms and plates, said pivotal connection being defined by aligned slots disposed in said plates and block walls and between said frame arms.

3. In a brake slack adjuster, the combination of: a frame comprising a pair of spaced arms, a wall interconnecting said arms and defining therewith a slot extending longitudinally of said frame, a unitary fulcrum block assembly in said slot and movable lengthwise thereof, said assembly comprising a fulcrum block including a pair of spaced side walls, a hub interconnecting said side walls and defining therewith a lever opening, slots in said side walls extending from their free ends toward said hub, spaced plates disposed between said arms and respective side walls, said plates spacing the side walls from the arms and having flanges overlapping corresponding edges of said arms, said side walls having flanges overlapping opposite corresponding edges of said arms, slots in said plates extending from the edges thereof remote from their flanges, the inner ends of the slots in the plates and the inner ends of the slots in the side walls being registered, a brake lever fulcrum pin journaled in all of said slots at their inner ends, means connecting the first-mentioned wall to the hub for adjusting the space between the hub and first-mentioned wall, and means connecting the plates to the side walls for movement therewith longitudinally of the slot.
